UNITED STATES PATENT OFFICE.

JOHN B. SWAN, OF GLADSTONE, MICHIGAN, ASSIGNOR OF ONE-HALF TO CHARLES F. SMITH, JR., OF RHINELANDER, WISCONSIN.

SAND-PIPE USED ON RAILROAD-LOCOMOTIVES.

1,118,247.

Specification of Letters Patent. Patented Nov. 24, 1914.

Application filed February 4, 1914. Serial No. 816,503.

To all whom it may concern:

Be it known that I, JOHN B. SWAN, a citizen of the United States, residing at Gladstone, in the county of Delta and State of Michigan, have invented a new and useful Improvement in Sand-Pipes used on Railroad-Locomotives, of which the following is a specification.

This invention relates to improvements in shields for sand pipes for locomotives and other like vehicles.

The object of the invention is to provide a sand pipe shield for cutting off the wind and for preventing water produced by condensation of moisture on the rails or from other sources from being blown or otherwise deposited on the pipe to which this shield is applied and forming ice at the bottom of said pipe, thereby avoiding choking of the pipe.

Another object is to provide a device of this character which concentrates the flow of sand on the rail and more especially at curves.

With the above objects in view, the invention consists of certain novel features of construction, combination and arrangement of parts as will be more fully described and claimed.

In the accompanying drawings: Figure 1 represents a side elevation of this improved guard or shield applied; Fig. 2 is a front elevation thereof; Fig. 3 is a perspective view on a reduced scale of this improved shield taken from the bottom; Fig. 4 is a perspective view with the pipe shown in dotted lines; Fig. 5 is a detail plan view of the securing clamp shown closed in full lines and open in dotted lines; Fig. 6 is a detail perspective of the gasket; Fig. 7 is a perspective view of the guard with the parts separate and arranged in juxtaposition ready for assembling.

In the embodiment illustrated, a sand pipe P is shown of ordinary construction and to which is applied this improved guard 1. This guard 1 comprises an outer skirt 2 and an inner skirt 3 flared at their tops for a portion of their length and each split longitudinally from top to bottom. The outer skirt 2 which is constructed of any suitable bendable sheet metal, has the edges of its slit diverged for any suitable or desired distance, about one third more or less and the remainder of said edges are parallel. This

skirt when applied, extends several inches below the lower end of the sand pipe P. Disposed within the skirt 2 is the inner skirt 3 slit throughout its length and its edges tapering toward its top from a point corresponding to a point at which the tapering begins on the outer skirt 2. This skirt 3 fits snugly within the skirt 2 at its top and conforms somewhat in shape thereto. The straight edges of the inner skirt 3 have outturned lips 4 which overlap the straight edges of the outer skirt 2 as shown in Fig. 4 and hold said skirts against lateral movement relatively to each other. The lower portion of the inner skirt 3 opposite its slit side is bent to form a funnel like member 5 for concentrating and directing the sand onto the track. The slit upper ends of the skirts 2 and 3 are closed by a transversely curved plate 6, the edges of which taper toward its upper end to adapt it to conform to the shape of the skirts 2 and 3. This closing plate 6 spans and closes the slit portions of the skirts 2 and 3 throughout their tapered portion leaving the part below open.

A rubber gasket in the form of a split ring 7 is designed to encircle the pipe P between it and the upper ends of the skirts to form a water tight connection at this point when the clamping ring 8 is applied. This clamping ring 8 is shown in detail in Fig. 5 and comprises two semi-circular members 9 and 10 hinged together at one end and provided at their free ends with laterally extending apertured lips through which a securing screw or bolt is adapted to pass for securing it in operative position on the pipe, said clamp being adapted to encircle the upper ends of the skirts over the gasket and thereby securely fasten the guard to the pipe.

In the use of this invention, when the skirts are clamped to the pipe P as above described, the lower edges thereof project several inches below the lower end of the pipe and the funnel shaped member of the inner skirt is positioned to direct the sand from the pipe and to concentrate it on the track over which the pipe is disposed, the flared lower end of the skirts protecting said pipe end from water of condensation or otherwise, such as is usually thrown against the pipe and combines with the sand, very often clogging and entirely stopping the opening in the pipe.

I claim as my invention:

1. A sand pipe protector comprising inner and outer skirts flaring throughout their length toward their bottoms and one of them having means at one side thereof for concentrating the flow of sand on the rail and means for securing said skirts to a sand pipe.
2. A sand pipe protector comprising inner and outer skirts flaring toward their bottoms, the inner skirt having means at one side thereof for concentrating and directing the flow of sand onto the rail, and means for securing said skirts to a sand pipe.
3. A sand pipe protector comprising inner and outer skirts, the inner skirt having a funnel-shaped element at one side for concentrating and directing the flow of sand onto the rail, and means for securing said skirt to a sand pipe.
4. A sand pipe protector comprising two flared longitudinally split skirts arranged

one within the other with the openings registering with each other, and a closure for the upper end of said split portions.

5. A sand pipe protector comprising two flared longitudinally split skirts arranged one within the other with the openings registering with each other, and a tapered plate overlapping the upper end of the split portions of said skirts.

6. A sand pipe protector comprising inner and outer skirts arranged one within the other and split longitudinally throughout their length, the inner skirt having outwardly extending backturned lips along the edges of the split portion thereof to receive the split edges of the outer skirt, whereby said skirts are held against lateral movement relatively to each other.

JOHN B. SWAN.
